PROTECTOR FOR USE IN HAIR WAVING APPARATUS

Emile J. Yven, Jackson Heights, N. Y., assignor to Clairol Incorporated, Stamford, Conn., a corporation of Connecticut

Application May 28, 1941, Serial No. 395,567

6 Claims. (Cl. 132—36.1)

This invention relates to improvements in hair waving devices, and is more particularly directed to a protector unit made of readily destructible material suitable for single application.

Up to the present time, considerable difficulty has been encountered in the industry by virtue of the successive and continuous use without cleaning or sterilization, of curlers, wrappers and protectors, with resultant complaint by fastidious customers.

It is an object of this invention to provide for a hair waving assembly, and particularly a protector unit therefor, incorporating a separable hair engaging or gripping member, which is constructed of readily destructible material of low cost suitable for single application.

These and other advantages, capabilities and features of the invention will appear from the subjoined detailed description of one specific embodiment thereof illustrated in the accompanying drawings, in which—

Figure 1 is a perspective plan view of the base of the protector unit forming the subject matter of this invention.

Figure 2 is a further perspective plan view of the same as spread for the reception of the absorbent hair gripping element of the unit.

Figure 3 is a rear view of the base of the protector unit.

Figure 4 is a plan view of the blank for the hair engaging element of the protector unit as scored and cut.

Figure 5 is a perspective plan view of the hair gripping engaging blank as folded.

Figure 6 is a perspective plan view of the protector unit with the hair gripping member thereof in position on the base.

Figure 7 is a perspective view of a complete hair waving assembly incorporating the protector unit as applied to the head of a subject.

Figure 8 is a side elevation in section taken along lines 8—8 of Figure 7.

The protector unit of a preferred embodiment of this invention comprises a base member, a separable hair engaging or gripping member mounted in such base member, both applied in association with mandrel and enclosure wrappers to form a hair waving assembly.

Referring to the reference characters in the drawings, the base member A of the protector unit comprises an elongated strip of paper board or similar molded and preferably porous and non-heat conducting material, slitted longitudinally as along 20 from one end thereof to a terminal in zone 21 adjacent the other end there-

of, thereby defining legs 22a and 22b, which may be laterally spread from one another to a slight degree to define an angular slot leading from the terminal serving as an apex, as shown in Figure 2.

5 A pair of mandrel supports comprising aligned upstanding cradles 23a and 23b are mounted respectively on leg 22a adjacent the open end of the base defined by the slit 20, each of the cradles 19 being carried on a stem 24 from which extends pronged legs 25 for fastening the supports to the base.

As shown in Figures 1 to 3, there are formed 15 respectively on the outer sides of legs 22a and 22b, and adjacent the open end of the base defined by the slit 20 and in alignment with one another, transversely extending slit 26a and angular notch 26b. A resilient clamping member, preferably an elastic, 27, is inserted along its 20 length within slit 26a for firm frictional mounting at a segment of its periphery, and is adapted upon being stretched or tensed to extend across and surround legs 22a and 22b as it enters into notch 26b, thereby drawing the legs towards one another sufficiently to substantially seal the slit 20 separating the same.

In the preferred embodiment of this invention, as specifically illustrated in Figures 4 to 8, there is mounted within the slit 20 an absorbent and pliable hair engaging member B shown respectively in blank form in Figure 4, in folded form in Figure 5 and in associated assembly form in relation to the base of the protector unit in Figure 6.

35 The hair engaging member is formed of a blank of pliable absorbent paper pulp or similar material and as shown in Figure 4 is scored along parallel lines 28a and 28b from one end thereof to a point adjacent the other end, and is cut 40 along the parallel lines aforesaid from such point to the other end to form slots 29a and 29b; intermediate of the parallel scoring lines there is formed a narrow slit 30 extending from the first named end to a point adjacent the 45 other end, from which point an aligned scoring line 31 is directed to the other end of the blank; the entrance end of the slit 30 being arcuately cut in opposing directions as at 32.

As shown in Figure 5, the scored and cut blank 50 is folded along the three scoring lines 28a, 28b and 31 to define a structure wherein this member comprises adjoining hair gripping walls 32a and 32b upstanding from supports 34a and 34b, the respective walls being merged along scoring line 31 to form a shoulder 35 which extends ver-

tically above a vertically extending cutout 36 defined by the spacing between the respective sides of each of the slots 29a and 29b.

To assemble the protector unit, the base member A is spread, as shown in Figure 2, and the hair gripping member B of Figure 5 is slid into the slit 20, with the walls 33a and 33b thereof upstanding within the slit, the supports 34a and 34b beneath and adjacent the underfaces of legs 22a and 22b, the shoulder 35 thereof extending over a portion of the zone 22 of the base and longitudinally beyond cradle 23b, which is disposed between the vertical reaches of the slot 36; the member being of such length that the arcuate portion 32 thereof extends longitudinally beyond cradle 23a.

In use, and referring particularly to Figures 6, 7 and 8, the protector unit incorporating the base and hair gripping members is spread open along the slit 20 similarly to the showing with respect to the base member alone in Figure 2, but at this time the respective walls and supports 33a and 34a on the one hand and 33b and 34b on the other are displaced with legs 22a and 22b of the base; a tress of hair H consisting of several strands is interposed between the spread legs and walls, and elastic 27 displaced and stretched from the position of Figure 2 to envelop the legs, supports and upstanding hair engaging walls aforesaid, adjacent cradle 23a so as to draw the legs and hair gripping walls towards one another and substantially seal the slit 20.

A non-reusable exothermic mandrel 37 of the character shown in my application, Serial No. 370,376, filed January 27, 1941, and about which the tress of hair is wound, is mounted in the cradles, an absorbent pad 38 incorporating hair waving material is wrapped about the mandrel 37 and the hair engaging walls 33a and 33b; and a water-proof wrapper, as for example, tin foil or waxed paper 39 or the like, is wrapped around the various elements disposed above the legs 22a and 22b of the base to form a complete enclosure for the same; and the entire enclosed assembly is locked by clamp 40 as shown respectively in Figures 7 and 8.

As heat is developed in the mandrel, and the hair wound on the mandrel is subjected to heat and vapor developed within the assembly, the upstanding opposing hair gripping walls 33a and 33b being of porous and absorbent material, are wetted by the vapors developed and become softened and expand and form a substantially vapor-tight sealing zone for the entire contiguous areas thereof along and between which extend the hair strands of the tress wound on the mandrel, this sealing effect being concurrent with that caused by the tension imparted to the hair gripping elements when the same are drawn towards each other by virtue of the action of the elastic 27 enveloping legs 23a and 23b.

Each and every element of this assembly, which in any way is in contact with the hair of the subject, is non-reusable and destructible, thus to provide for sanitary, single application in processes for permanently waving the hair, along the lines of my application, Serial No. 277,135, filed June 3, 1939, of which this application is a continuation-in-part.

Although I have described the assembly as being non-reusable and destructible, it is within the province of this invention to apply a protector unit wherein the slotted base may be formed of material capable of reuse in conjunction with an

interchangeable non-reusable head engaging or gripping member readily mountable therein.

It is obvious that various changes and modifications may be made to the details of construction without departing from the general spirit of the invention as set forth in the appended claims.

I claim:

1. A non-reusable scalp protector for use in permanent waving and made of readily destructible material suitable for single application, comprising a slotted base, a hair gripping element separably mounted on said base, and having upstanding walls extending through the slit thereof, and resilient means for drawing the portions of the base bounding the slit and the upstanding parallel walls of the hair gripping element towards one another, whereby to lock the hair gripping element within the slit and to seal the slit.
2. A non-reusable scalp protector for use in permanent waving and made of readily destructible material suitable for single application, comprising a base having a longitudinal slit open at one end, a hair gripping element comprised of a strip of absorbent material folded to provide parallel upstanding hair gripping surfaces, slidably mounted on the base with the upstanding gripping surfaces thereof extending through the slit, and means for drawing the portions of the base adjacent the open end of the slit towards one another, whereby the upstanding hair gripping surfaces of the hair gripping element are drawn towards one another, to seal the space therebetween and the slit of the base.
3. A non-reusable scalp protector for use in permanent waving and made of readily destructible material suitable for single application, comprising a slotted base, spaced upwardly extending mandrel supports adjacent the slit, a hair gripping element having parallel porous surfaces extending upwardly through the slit removably mounted on the base, and means for drawing the portions of the base bounding the slit and the upwardly extending surfaces of the hair gripping element towards one another, thereby to seal the space therebetween and the slit.
4. A non-reusable scalp protector for use in permanent waving and made of readily destructible material suitable for single application, comprising a base slotted from one end to a point adjacent the other end thereof, a hair gripping element separably mounted on the base and comprising a strip of absorbent material folded to provide parallel upstanding walls extending through the slit, means for locking the hair gripping element to the base against vertical movement, and resilient means for drawing the portions of the base bounding the open end of the slit, and the upstanding walls of the hair gripping element towards one another, thereby to lock the hair gripping element to the base against lateral movement, and seal the space between the walls of the hair engaging element and the slit.
5. A non-reusable scalp protector for use in permanent waving and made of readily destructible material suitable for single application, comprising a slotted base, a hair gripping element separably mounted on said base, and having porous upstanding parallel walls expansible upon wetting extending through the slit thereof, and resilient means for drawing the portions of the base bounding the slit and the upstanding walls of the hair gripping element towards one

another, whereby to lock the hair gripping element within the slit and to seal the slit.

6. A non-reusable scalp protector for use in permanent waving and made of readily destructible material suitable for single application, comprising a slitted base, a hair gripping element comprised of a strip of absorbent material expansible upon wetting folded to provide parallel upstanding hair gripping surfaces, slidably

5 mounted on the base with the upstanding gripping surfaces thereof extending through the slit, and means for drawing the portions of the base adjacent the slit towards one another, whereby the upstanding hair gripping surfaces of the hair gripping element are drawn towards one another to seal the space therebetween, and the slit of the base sealed.

EMILE J. YVEN.
